UNITED STATES PATENT OFFICE.

MAX LANGMAN, OF NEW YORK, N. Y.

BLOOMER-SKIRT.

1,095,895.

Specification of Letters Patent. Patented May 5, 1914.

Application filed September 13, 1913. Serial No. 789,638.

To all whom it may concern:

Be it known that I, MAX LANGMAN, a citizen of the United States, and a resident of the city of New York, borough of Brooklyn, in the county of Kings and State of New York, have invented a new and Improved Bloomer-Skirt, of which the following is a full, clear, and exact description.

The invention relates to female wearing apparel, and its object is to provide a new and improved bloomer skirt more especially designed for use when exercising, bathing, swimming, riding or the like, and arranged to provide the desired fullness in the skirt, and to permit free movement of the legs for exercising purposes thus insuring the desired comfort.

In order to accomplish the desired result use is made of bloomers having integral overlapping front flaps, integral overlapping rear flaps, and fastening means on the flaps for fastening the flaps together with a view to provide a skirt effect.

A practical embodiment of the invention is represented in the accompanying drawings forming a part of this specification, in which similar characters of reference indicate corresponding parts in all the views.

Figure 1 is a front perspective view of the bloomer skirt as applied and with the front skirt flaps open and turned back and the placket partly opened; Fig. 2 is a rear perspective view of the skirt with the rear skirt flaps partly open and turned back and with the sanitary flap partly open; Fig. 3 is a perspective view of one half of the bloomer skirt; Fig. 4 is a face view of one of the two pieces for forming the bloomer skirt; Fig. 5 is a sectional plan view of the bloomer skirt with the front and rear flaps closed to provide a skirt effect; and Fig. 6 is a similar view of the same with the legs of the bloomers gathered and the front and rear flaps open to provide bloomers without the skirt effect.

The garment combines bloomers A provided with front skirt flaps B, B', rear skirt flaps C, C', a waist D and a waistband E common to both the bloomers A, the flaps B, B', C, C', and the waist D. The waistband E is open at the front and provided with a fastening device E' in the form of a button and buttonhole or the like, as plainly indicated in Fig. 1. The waistband E is provided at the back of the garment with two tabs F (see Fig. 2) extending toward each other and each adapted to be but-

toned to one of a series of buttons F' attached to the waistband E to change the waistband with a view to snugly fit persons of different waist measure.

By reference to Fig. 2 it will be noticed that the free ends of the tabs F are spaced apart and the fastening devices for fastening the tabs to the waistband are independent one of the other, thus allowing adjustment of the tabs independently one of the other. By this arrangement the waistband can be minutely adjusted to accurately fit the waist of the user.

The bloomers A and the skirt flaps B, B' and C, C' are formed from two pieces of fabric material, alike in construction, each piece being of the shape shown in Fig. 4. Each piece consists of a central panel G, side flaps H, H' and folds B², C² intermediate the central panel G and the flaps H, H' to form doubled-up skirt flaps B and C (B', C'). The folds B², C² are doubled up and fastened together by stitches B³, C³ at the junction of the sides of the panel G with the side flaps H, H', as plainly indicated in Figs. 5 and 6. The central panel of each piece is provided with a cut-out portion G', one side wall of which is formed into a placket flap I and the other side wall is formed into one-half of a sanitary flap J. The folds B² when doubled up are sewed together to form the front and rear skirt flaps B and B' and C, C', as previously mentioned, and the outer edges of the side flaps H, H', are sewed together to form hip seams H², and the edges of the cut-out portion G' of the two pieces are sewed together to provide the garment at the front with the placket I and at the rear with the sanitary flap J. The upper edges of the pieces are fastened to the waistband E to which is also fastened the waist D to complete the garment. Suitable fastening devices I', such as buttons and buttonholes are provided to fasten the placket flaps I together at the front of the garment, and suitable fastening devices J', such as buttons and buttonholes, are provided along the margin of the sanitary flap J and the opening thereof to hold the sanitary flap J normally in closed position but to allow of opening said flap whenever it is desired to do so.

The skirt flaps B, B' and C, C' are adapted to overlap and are provided with fastening devices K, such as buttons and buttonholes for closing the overlapping flaps at the front and at the rear of the garment. It is

understood that when the skirt flaps B, B' and C, C' are in closed and fastened position a skirt effect is provided and the bloomer legs are not visible. When it is desired to exercise, swim or ride then the user unfastens the skirt flaps B, B', C, C', gathers the bloomer legs and fastens the same in the gathered position by the use of tabs L secured to the bloomer legs at the junction of the panel G with the side flaps H', the tabs L being adapted to engage buttons L' attached to the bloomer legs at the junction of the side flaps H with the panel G, as will be readily understood by reference to Figs. 5 and 6. By the arrangement described the user of the garment has free movement of the legs for exercising purposes, but when not exercising the tabs L are unfastened from the buttons L' and the skirt flaps B, C and B', C' are fastened together by the fastening devices K to provide a full skirt effect.

From the foregoing it will be seen that the bloomer skirt is formed of two single pieces of a fabric material, and but little fabric material is required to form a bloomer skirt.

Garters N for holding up the stockings are provided inside the bloomer legs and each garter N is attached to the lower end of a band N' of elastic or other material and secured at its upper end to the upper portion of the corresponding panel G, as plainly indicated in Fig. 3.

The waist D is adapted to be opened at the front by suitable fastening devices O, such as buttons and buttonholes, and the waist is also provided at the front with a change pocket P for containing coins, jewelry or other articles.

Having thus described my invention, I claim as new and desire to secure by Letters Patent:

1. A garment provided with a combined skirt and bloomers made of two pieces, each piece having a central panel, side flaps and doubled-up folds intermediate the said central panel and the said side flaps, the inner edges of the doubled-up folds being secured to the adjacent edges of the said central panel and the said side flaps, the pieces being fastened together along the median center line of the said central panels and the outer edges of the said side flaps of each piece being fastened together, the side flaps and the said central panel forming bloomer legs.

2. A garment provided with a combined skirt and bloomers made of two pieces, each piece having a central panel, side flaps and doubled-up folds intermediate the said central panel and the said side flaps, the inner edges of the doubled-up folds being secured to the adjacent edges of the said central

panel and the said side flaps, the pieces being fastened together along the median center line of the said central panels and the outer edges of the said side flaps of each piece being fastened together, the side flaps and the said central panel forming bloomer legs, and a waistband on which the upper edges of the two pieces are secured together.

3. A garment provided with a combined skirt and bloomers made of two pieces, each piece having a central panel, side flaps and doubled-up folds intermediate the said central panel and the said side flaps, the inner edges of the doubled-up folds being secured to the adjacent edges of the said central panel and the said side flaps, the pieces being fastened together along the median center line of the said central panels, and the outer edges of the said side flaps of each piece being fastened together, the side flaps and the said central panel forming bloomer legs, the outer edges of the doubled-up front and rear folds being adapted to overlap, and fastening devices on the said outer edges of the doubled-up folds for fastening the overlapping outer edges together.

4. A garment provided with a combined skirt and bloomers, made of two pieces, each piece having a central panel, side flaps, and folds intermediate the said central panel and the side flaps, the pieces being fastened together along the said central panel, and the outer edges of the side flaps of each piece being fastened together to form bloomer legs, the front of the bloomers having a placket and the rear of the bloomers being provided with a sanitary flap terminating a distance below the upper edge of the bloomers, and a waistband on which the upper edges of the two pieces are fastened together.

5. A garment provided with a combined skirt and bloomers, made of two pieces, each piece having a central panel, side flaps, and folds intermediate the said central panel and the side flaps, the pieces being fastened together along the said central panel, and the outer edges of the side flaps of each piece being fastened together to form bloomer legs, a waistband on which the upper edges of the two pieces are fastened together, and adjusting tabs secured to the waistband at the back of the garment and fastening means on the waistband for engagement by the said tabs to adjust the size of the waist.

In testimony whereof I have signed my name to this specification in the presence of two subscribing witnesses.

MAX LANGMAN.
